UNITED STATES PATENT OFFICE.

HARVEY L. BRYANT, OF NEWARK, NEW JERSEY, ASSIGNOR TO AMERICAN CAN COMPANY, OF NEW YORK, N. Y., A CORPORATION OF NEW JERSEY.

DRIER.

Application filed August 8, 1921. Serial No. 490,516.

To all whom it may concern:

Be it known that I, HARVEY L. BRYANT, a citizen of the United States, residing in Newark, in the county of Essex and State of New Jersey, have invented a new and useful Improvement in Driers, of which the following is a specification.

This invention relates in general to drying apparatus, and in the particular embodiment illustrated in the drawings, it is shown as utilized in a combined lining and drying machine used in the compound gasket lining of can covers. In this type of gasket lining it is essential that the covers and the compound gasket material deposited in the flanges thereof shall be thoroughly dried prior to the application of the covers to can bodies. While my invention is particularly adapted for use in conjunction with the apparatus employed for this purpose, it will be understood that it has much broader application, and may, from certain aspects, be considered as a general improvement in conveyor and handling means for can covers and other like articles.

A principal object of the invention is the provision of a drying apparatus having conveyor means for simultaneously moving a plurality of superimposed or aligned covers through a drying chamber.

A further object of the invention is the provision in conjunction with an apparatus of this character of automatic feeding mechanism whereby the covers are rapidly and efficiently fed from a lining machine to a plurality of guideways provided in the drying chamber.

A still further object of the invention is the provision in an apparatus of the foregoing general character of means for discharging the dried covers from the apparatus in vertically stacked relationship.

Still another object of the invention is the provision of associated cover lining and drying apparatus in which the same power means is utilized to operate both the liner discharge and drier conveyors, and in which efficient means are provided for transferring the covers from one conveyor to the other, the entire mechanism comprising relatively

few parts, and being certain, rapid and effective in operation.

Numerous other objects and advantages of the invention will be apparent as it is better understood from the following description, which, taken in connection with the accompanying drawings, discloses a preferred embodiment thereof.

Referring to the drawings,

Figure 1 is a plan view partially in outline, of associated cover liner and drying machines upon which my invention is employed;

Fig. 2 is an enlarged side elevational view of a portion of the rear end of a drying apparatus;

Fig. 3 is an enlarged vertical section taken substantially on the line 3—3 in Fig. 1;

Fig. 4 is an enlarged side elevation of the receiving side of the drying apparatus, showing the means for transferring the lined covers to the drier conveyor;

Fig. 5 is an enlarged plan view of an end of the drying apparatus showing both the feeding in and discharge mechanism;

Fig. 6 is an enlarged transverse partial section of the liner discharge conveyor and showing also the means for feeding the lined ends thereto; and

Fig. 7 is an enlarged transverse section taken through both conveyors showing the means for transferring the covers from the one to the other.

The drawings disclose an apparatus in which my invention is preferably employed, and in them I have shown in outline form a number of machines 11 for the compound gasket lining of can covers, and a drying apparatus associated therewith and generally indicated by the reference character 12. In the lining machines 11 the flanges of the can covers are lined with compound gasket material and are delivered therefrom and fed into a discharge conveyor frame 13 by means of a feeding chain 14 which is trained over vertically disposed sprockets 15 and has protruding therefrom at intervals lugs 16 adapted to move the covers upon a track 17 and into an appropriate guideway 18 provided in vertical series in the conveyor

frame 13, this mechanism being best illustrated in Fig. 6. The covers are feed individually into the separate guideways 18, and for this purpose the conveyor frame 13 is 5 so constructed as to permit the feeding of the covers from the different machines at varying levels, the particular guideway which is to receive a cover at a given position being provided at the side opposite the 10 feeding mechanism with a flared mouth, as indicated at 19. A chain conveyor 21 driven by a sprocket 22 is mounted to travel through a channel 23 in the central part of the conveyor frame 13 and has upstanding 15 lugs or flights 24 thereon which are adapted to propel the covers through the guideways 18.

The drying apparatus 12 is positioned beyond the lining machine, and, in the present instance, is in the form of a U-shaped 20 chamber 25, the open ends of which are shown in Fig. 5. This chamber is supported upon legs 26 cross connected by bars 27, and has at the base of the U a flue or 25 stack 28, or other means of discharging the heated air. It will be understood that the 30 drying chamber may be heated in any desired manner either by a series of burners or by introducing heated air into the open 35 ends thereof. A top cover 29 is secured in place by means of screws 31 and the chamber is provided with aligned recesses 32 in its opposed walls, each pair of these recesses forming a guideway or track for a single 40 can cover, and they being provided in vertical series to any height desired. The frame or body 33 of the drying chamber is 45 interiorly grooved as at 34 to provide a channel guide for a chain conveyor 35, this conveyor being driven and guided about horizontally disposed sprockets 36 and 37 and passing entirely through said drying 50 chamber. The conveyor 35 is provided with lugs or flights 38 projecting upwardly from the channel guides 34 and between the opposed recesses 32.

By reference to Figs. 1 and 5, it will be observed that the discharge conveyor from the lining machines and the drier conveyor, 55 just described, are arranged in overlapping position, and means are provided for transferring the lined covers from said discharge conveyor to the guideways 32 in the drying chamber. The discharge conveyor is cut away at the point 39 adjacent which point the side wall of the drying chamber is left open so that the covers 41 may pass directly into the guideways 32. A pusher bar or lever 42 is provided at the point of registration of the cut away portion of said discharge conveyor and the open wall of said chamber. This pusher member is pivoted to the frame of the machine by a collar 43 from which protrudes an arm 44 carrying 60 a roller 45 which rides upon a cam member

46 which rotates with a power shaft 47. A spring 48 serves to keep said roller in contact with said cam and to operate the pusher head 49 intermittently and in synchronism with the rotation of the shaft 47. Thus, 70 the covers are transferred from the guideways 18 in the conveyor frame 13 to the registering guideways 32 in the drying chamber. The covers in all the guideways 75 32 are then engaged by one of the lugs 38 of the conveyor 35 and are simultaneously moved thereby entirely through the U-shaped chamber in which they are dried. It will be understood that this last mentioned conveyor is driven by means of the 80 sprocket 36 through suitable gear connection with the shaft 47, the pinion 51, the gear 52 and the sprocket chain 53 and wheel 54 providing that connection in the present instance. The shaft 47 is rotated by means of a motor 55, through a pinion 56 and suitable gearing in the casing 57, and it will be noted that the sprocket 22 driving the conveyor 21 is also driven by the rotation of the shaft 47 through the instrumentality of a pinion 58, a gear 59 and a driving chain 61.

Referring now to Fig. 5, the novel discharge mechanism which I have provided may be observed near the discharge end of the drying chamber. The uppermost track 62 of the series of guideways 32 is cut away, as indicated at 63 to permit the cover carried upon that track to fall upon the cover carried upon the next lower track. Said latter track is cut away as at 64 in similar manner and the remaining tracks are successively cut away as indicated in Fig. 5. Thus, as the covers approach the end of the drying chamber they are stacked one upon the other and they are discharged through an inclined guideway 65 which is positioned at the extreme end of the drying chamber and so arranged as to remove the covers from control of the conveyor 35 and to deliver them in desired stacked relationship for subsequent handling.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. An apparatus for drying gasket lined can covers, comprising a drying chamber, guideways in said chamber for a plurality of superimposed covers and single conveyor means for moving said covers through said guideways.
2. An apparatus for drying gasket lined

can covers, comprising a drying chamber, a series of separated aligned guideways disposed vertically with respect to each other and single conveyor means for moving a plurality of covers simultaneously through said guideways.

3. An apparatus for drying gasket lined can covers, comprising a drying chamber, a plurality of guideways in said chamber, means for delivering can covers into each of said guideways and single means for moving a plurality of covers simultaneously through said guideways.

4. An apparatus for drying gasket lined can covers, comprising a drying chamber having a plurality of guideways arranged in vertical series, automatic means for delivering a lined can cover into each of said guideways, and a conveyor having lugs, each adapted to propel a plurality of vertically aligned covers through said guideways.

5. An apparatus for drying gasket lined can covers, comprising a drying chamber, a series of guideways in said chamber, single means for propelling a plurality of can covers through said guideways, and means for discharging the dried covers from said chamber in superimposed relationship.

6. An apparatus for drying gasket lined can covers, comprising a drying chamber, a series of guideways in said chamber, single means for propelling a plurality of can covers through said guideways, and discharge means adapted to deliver the dried covers from said chamber in vertically stacked relationship.

7. An apparatus for drying gasket lined can covers, comprising a drying chamber, a plurality of aligned recesses in the opposite sides of said chamber and forming together a plurality of centrally interrupted guideways arranged in vertical series, means for delivering lined covers individually into said guideways, and a conveyor having lugs, each adapted to extend into the space between said aligned recesses and to simultaneously propel a plurality of said covers through said chamber.

8. In combination a machine for gasket lining the flanges of can covers, a conveyor for removing the lined covers from said lining machine, means for individually delivering the covers from said machine to said conveyor, a drying chamber having a plurality of guideways in its opposed walls, means for transferring the covers from said removing conveyor to said guideways, and conveyor means moving through said chamber and having individual lugs, each adapted to simultaneously propel a plurality of superimposed covers through said guideways.

9. In combination a machine for gasket lining the flanges of can covers, a conveyor for removing the lined covers from said

lining machine, means for individually delivering the covers from said machine to said conveyor, a drying chamber having a plurality of guideways in its opposed walls, automatic means for transferring the covers from said removing conveyor to said guideways, and conveyor means moving through said chamber and having individual lugs, each adapted to simultaneously propel a plurality of superimposed covers through said guideways.

10. In an apparatus for drying gasket lined can covers, conveyor means comprising a plurality of guideways arranged in vertical series and single means for propelling a plurality of superimposed can covers through said guideways.

11. In an apparatus for drying gasket lined can covers, conveyor means comprising a plurality of guideways arranged in vertical series and automatic discharge means adapted to deliver the covers from said guideways in vertically stacked relationship.

12. An apparatus for drying gasket lined can covers, comprising a drying chamber having a plurality of horizontally aligned recesses in its opposed walls, each pair of said recesses forming a cover guideway, single conveyor means for propelling a plurality of covers through said guideways, and means for discharging the dried covers from said chamber in superimposed relationship, said means comprising a succession of steps formed by cutting away the guideways successively from top to bottom near the discharge end of the chamber, said steps terminating in a discharge guideway.

13. In combination, a plurality of machines for gasket lining the flanges of can covers, a conveyor movable successively past said machines and receiving the gasket lined covers therefrom, and a drying chamber into which said covers from the several gasket liners are delivered by said conveyor.

14. In combination, a plurality of machines for gasket lining the flanges of can covers, a conveyer mechanism associated with said machine and receiving said covers in successive relation and conveying said covers from the several machines in non-interfering positions, and a drier for drying the gasket material.

15. In combination, a plurality of machines for gasket lining the flanges of can covers, a conveyer movable past said machines, guides associated with said conveyer and receiving and maintaining the covers received from different machines at different levels.

16. In combination, a plurality of machines for gasket lining the flanges of can covers, a conveyer for removing the lined covers from said lining machines, and a

drying chamber to which said covers are delivered from said machines, said drying chamber having a plurality of superimposed guideways each receiving the covers from a single machine.

17. An apparatus for drying gasket lined can covers, comprising a U-shaped chamber closed on the inside and outside and

open at the ends, a horizontal movable conveyer having a leg movable down one leg of said U-shaped chamber and the return leg of the conveyer movable up the other leg of the chamber, and means delivering a gasket lined can cover to said conveyer at the entrance side of said chamber.

HARVEY L. BRYANT.
